(57) **CLAIM**

I claim the ornamental design for a nipple for bottle, as shown and described.

DESCRIPTION

FIG. 1 is a top perspective view of the nipple for bottle mounted in a bottle cap;

FIG. 2 is a top perspective view of the nipple for bottle showing my new design;

FIG. 3 is a bottom perspective view thereof;

FIG. 4 is a front elevation view with the rear and side views being identical;

FIG. 5 is a top plan view thereof; and,

FIG. 6 is a bottom view thereof.

The broken lines in the drawings depict environmental subject matter only and form no part of the claimed design.
